UNITED STATES PATENT OFFICE.

CHESTER W. CLARK, OF MISHAWAKA, INDIANA.

BOOT-TREE.

SPECIFICATION forming part of Letters Patent No. 501,133, dated July 11, 1893.

Application filed February 1, 1893. Serial No. 460,572. (No model.)

To all whom it may concern:

Be it known that I, CHESTER W. CLARK, of Mishawaka, in St. Joseph county, in the State of Indiana, have invented a new and useful Improvement in Expansible Boot-Trees Adapted to the Treeing of Wool Boots; and I do hereby declare that the following is a full and accurate description of the same, reference being had to the accompanying drawings, wherein—

Figure 1 is a longitudinal elevation of my tree, partly in section, collapsed and within the unstretched boot. Fig. 2 is a similar elevation showing the tree in operation within the boot. Fig. 3 is a transverse section on line $x-x$ looking from above. Fig. 4 is a transverse section on line $y-y$. Fig. 5 is a transverse section on line $z-z$ looking toward the toe. Fig. 6 is a perspective of the hollow heel. Fig. 7 is a longitudinal section showing a modification in the foot. Fig. 8 is a transverse section on line $w-w$.

A woolen boot may be made in one of two ways, first of a wool bat roughly shaped like a gigantic boot, or by knitting coarse, loosely spun yarn in the form of a gigantic stocking. In either case it is caused to shrink and full by treatment in hot water or steam in a fulling machine of some description. The former is converted into true felt. In the latter the felting process is partly interfered with by the twisting of the wool into yarn, but in either case the fabric comes from the fulling mill in the form of an irregular conical bag of young felt hard and stiff, which it is required to shape on proper "trees" while yet wet. The hard and stubborn condition of the felt renders the labor of treeing severe, the more so, since it is necessary to handle the boots while still soaked in hot water.

My invention is designed to facilitate the operation of "treeing" and to lighten the hardship of that labor. It is also designed to treat the fabric more equably and reduce the percentage of boots spoiled in the process of treeing.

It will be understood that after the felt bag has been shaped by the tree it is placed in a drying oven and is not removed from its tree until entirely dry after which it will retain its shape indefinitely. Heretofore mechanical trees have been constructed with elongat-

ing legs and feet, so that in treeing the felt has been stretched out, especially on a line along the back of the leg, heel and sole, but 55 the structure of the elongating leg has been to concentrate the stretch mostly at the heel, because the upper part of the leg resting upon the non moving part of the leg refuses to slide thereon under the strain of the extending portion of said leg. Therefore in many boots shaped upon said trees the heel portion was stretched out too thin or ruptured entirely, and in either case, the boot was spoiled. Owing to this defect in mechanical 65 or expanding trees, so far as known to me, felted wool-boots are still exclusively treed upon trees expanded by wedges in the primitive way.

My invention obviates the defects of the 70 mechanical trees as heretofore made, and also obviates the greater part of the labor incident to the hand process.

My tree consists of three members: two leg pieces A. and B. and a foot piece C pivoted to the leg pieces in such manner that as the leg pieces are caused to move longitudinally as to each other, the foot piece will be caused to leave its initial position in line with said leg pieces, and assume a position at right angles thereto, viz: the relative positions of leg and foot. Incidentally the leg pieces A and B. are also moved away from each other to expand and shape the leg, and the foot piece is forced into the point or toe of the bag and 85 the foot portion is stretched and turned up to its proper position. When the boot has been properly formed and stretched by the action of the parts of the tree, it must be locked or retained in its position until the fabric 90 has become dry and thereby deprived of the power to revert to its original form. For this purpose I have placed an arm d upon the leg piece A. and provided the part B. with a proper catch e, to engage with the notch p. in 95 the end of the arm d. and thereby lock the parts. The arm d also serves as a guide for the movement of the part A. in expanding the leg. It will appear obvious that the arm d would be just as effective if projected in a 100 reverse direction (downward) from the part B.

When the treeing is to be done, the tree is collapsed as indicated in Fig. 1. and in that shape is inserted into the conical felt bag R.

before mentioned. A lever *k*, is then applied at the free ends of the parts A. B. and the part A is forced downward and outward and to the position shown in Fig. 2 guided by the 5 arm *d* to expand the boot. As stated above, in other mechanical trees the action is such that the stretch, necessary to the change of position and proper shaping of foot and heel, takes place at, and in immediate vicinity of 10 the heel and in my tree this necessary stretch is distributed over the whole length of the leg and foot and hence is accomplished without risk to the fabric, or undue stretching at the heel. To accomplish this, it is necessary 15 to hold the upper edge of the boot fabric on the side where the leg piece moves, independently of said moving piece, so that while said part is moving and exerting pressure on the heel, the upper edge being independently 20 held, the heel stretch will distribute itself over the whole length of the leg.

The upper edge of the leg may be held as described by a support attached to the leg piece B, but I have found it more economical 25 to make it separate from the tree and attached to a table upon which the tree may be placed while the boot fabric is being stretched. Therefore I have placed upon a suitable table one or more clips or blocks *m*, 30 which are preferably concave on the front to approximately fit the transform of the boot tree. These clips or blocks are rigidly secured to the table. A movable or pressure clip *N* is placed upon a strong spring or elastic arm *Q* which is also rigidly attached to said table in such position that the normal position of said clip *N* will be forward close to the clips *m. m.* The clip *N* is furnished with 35 teeth or such saw tooth corrugations as may be necessary to enable it to seize and hold the felt of the boot fabric, near to the upper edge thereof, while also pressing it against the moving part A, while the same is moving. Instead of a spring, the clip *N* may be 40 mounted upon an arm pivoted to said table, and forced against the moving part of the tree by foot pressure on a treadle or other 45 convenient way.

The tree as shown in Fig. 7 is a modification 50 of the tree above described in having the foot piece C' made in two parts hinged together at the toe, and therefore expandable as is the leg portion. In its general mode 55 of operation it does not differ from that shown in other figures. The parts A. B. C are concave shells in general shape adapted to the form of the leg and foot. They are provided interiorly with proper lugs, &c., for articulating attachments. They are also 60 pierced with numerous holes so that the air may have access to the inner surface of the fabric to facilitate the process of drying. For convenience in manufacture, the foot piece C is cast in two pieces which are after- 65 ward united. The upper or instep portion is pivoted at S near the instep to the front leg piece B. and the under or sole portion is

provided with an arm *h*, which, at its extremity is pivoted at T to the back leg piece A. the heel portion U of which is hollow and 70 is slotted as at V to permit said arm to fall into line with said leg piece when the tree is collapsed, as shown in Fig. 1. by passing into said notch. Therefore a longitudinal movement of the leg piece A. causes the heel 75 to be depressed, and the foot piece to swing upward on the instep joint to the proper foot position as in Fig. 2.

The modified structure of the foot piece C' shown in Figs. 7 and 8, wherein the two parts 80 of the foot piece are collapsible, being jointed together at the toe, makes it desirable that a stop shall be employed to limit the movement of said parts. I have employed the hooking plates *r. r.* for this purpose. 85

I do not herein claim and I hereby disclaim the combination, in a boot treeing machine, with a collapsible last supporting the mitten, of a holder engaging the exterior surface of the mitten, and bearing directly against the 90 last.

Having described my invention, I claim as new—

1. In an expandible boot tree, the leg pieces A and B and the foot piece the sole whereof 95 is formed in one rigid piece and is pivoted to the leg piece A. and the instep whereof is pivoted to the leg piece B. substantially as and for the purpose set forth.

2. The leg pieces A. B. combined with the 100 foot piece provided with the extended arm *h*, rigid with the sole portion of the foot piece, and the pivots whereby said foot piece is jointed to said leg pieces respectively for the purpose set forth. 105

3. The leg piece A. provided with the rigid arm *d*. and the leg piece B. provided with the catch *e*. combined with the foot piece jointed to said leg pieces respectively as and for the purpose set forth. 110

4. The leg piece B. the foot piece pivoted thereto at the instep, the arm *h* rigid with and extending from the sole portion of said foot piece, and the leg piece A. provided with a hollow heel having its bottom portion 115 slotted to give proper form to the fabric at that point and to permit said arm *h* to come in line with said leg piece A. when the tree is collapsed.

5. An expanding tree A. B. combined with 120 a foot-piece the fixed clips *m. m.* and the movable clip *N* adapted to seize and hold the boot fabric near its upper edge, independently of the moving part of said tree as set forth. 125

6. In a collapsible boot tree, comprising a stationary and a movable leg portion an arm *d* rigid with one of said portions to expand and sustain the parts of the tree, substantially as set forth.

CHESTER W. CLARK.
In presence of—
R. D. O. SMITH,
ELLIOTT F. ALDRICH.
